UNITED STATES PATENT OFFICE.

OTTO HOHEISEN, OF BIRKENFELD, NEAR PFORZHEIM, GERMANY.

DESIGN FOR A DEVICE FOR PEELING ORANGES.

46,867.

Specification for Design.

Patented Jan. 19, 1915.

Application filed November 25, 1913. Serial No. 803,050. Term of patent 7 years.

To all whom it may concern:

Be it known that I, OTTO HOHEISEN, a subject of the German Emperor, and resident of Birkenfeld, near Pforzheim, Germany, have invented a new, original, and ornamental Design for Devices for Peeling Oranges, of which the following is a specification, reference being had to the accompanying drawing, forming part thereof.

Figure 1 is a side view, and Fig. 2 a front view, of my new design.

I claim:—

The ornamental design for a device for peeling oranges, as shown.

OTTO HOHEISEN.
